(57) CLAIM

I claim the ornamental design for a pot lid holder, as shown and described.

DESCRIPTION

FIG. 1 is a perspective view of a pot lid holder;
FIG. 2 is a front view of the pot lid holder of FIG. 1;
FIG. 3 is a back view of the pot lid holder of FIG. 1;
FIG. 4 is a right-side view of the pot lid holder of FIG. 1;
FIG. 5 is a left-side view of the pot lid holder of FIG. 1;
FIG. 6 is a top view of the pot lid holder of FIG. 1;
FIG. 7 is a bottom view of the pot lid holder of FIG. 1; and,
FIG. 8 is an environmental view of the pot lid holder of FIG. 1.

Broken lines in FIG. 7 represent portions of the article and form no part of the claimed design.

The depicted pot lid holder features a unique appearance over the prior art. The pot lid holder comprises a pocket with a hand-hold on top and vents on the side.
